UNITED STATES PATENT OFFICE.

BERT L. HERRICK, OF OAKLAND, CALIFORNIA.

BAG OR NET FASTENER.

Application filed December 19, 1922. Serial No. 607,820.

To all whom it may concern:

Be it known that I, BERT L. HERRICK, a citizen of the United States, residing in the city of Oakland, county of Alameda, and 5 State of California, have invented a new and useful Bag or Net Fastener, of which the following is a specification.

This invention relates to improvements in devices for fastening around the neck of a 10 bag to hold the same closed, and in particular, relates to an improvement of this character, for which a patent was granted to me October 3, 1922, numbered 1,430,806 and titled Bag or net fastener.

15 In commercial laundries, it is customary to inclose certain classes of individual wash in separate bags made of fabric or netting, and close the same for general handling, before, during and after the washing process 20 or operation. When ready for the wash, a number of these bags are thrown into a washing machine and subjected to the washing operation. The present closure devices for the bags and with which I am familiar, 25 now and then open during the tumbling washing process, and cause annoyance, trouble and confusion, resulting in loss of time and involving more or less serious difficulty in identifying the individual belongings, 30 and which very frequently necessitates that the remaining unidentified pieces must be taken to all the customers who were assigned the unfortunate bags, for individual identification and claim.

35 The prime object of my invention is to overcome the above deficiencies by rendering the fastening secure against the accidental opening of the bag.

Another object is to render the securing 40 means easy to open, when its opening is desired.

A further object is to provide a guard for the tongue of the device, to prevent the neck or any portion of the bag from contacting 45 the said tongue and causing its depression and thereby making possible, under certain conditions, the release of the engaged link from service and rendering the bag openable.

A still further object is to prevent the 50 neck of the bag from slipping through the closed and engaged fastener, by providing an upwardly projecting lip from the interior of the device, to engage the mesh of the bag when slippage of either the bag or fastener 55 occurs.

With the above and some minor objects in view, my invention consists in certain novel features of construction, form and arrangement of parts, shown in the accompanying sheet of drawings and which form a part of 60 this specification and illustrates an embodiment of my invention. What I claim as new, is particularly pointed out in the appended claims following the specification.

In the drawings:

Figure 1 is a perspective view of the bag fastener when open. Figure 2 is a plan of it as it appears when closed. Figure 3 is a view of the device in the hand of an operator compressing the same, showing the position 70 the link assumes when so compressed. Figure 4 is a cross-section on an enlarged scale, of the device on the line A—A of Figure 2, showing primarily, the guard and tongue relation, and Figure 5 is a similar section on 75 the line B—B showing the lip.

In the figures:—The numeral 1 represents a piece of metal, preferably a flat strip of spring-material such as brass or copper, and is bent back as at 2, to bring the two ends 80 into proximity when closed.

The sides of the body of the device are formed by preference, with flat curvatures as shown in Figure 2, to enhance its resiliency. One of the ends as 3, is turned inward and formed into an inturned hook 4, whose extremity is chamfered to present a sharp edge 5, for a purpose to be presently described. The other end of the body 1 is formed into an eye 6, in which is hinged a 85 wire link 7, adapted to engage the hook 4 and so hold the two ends of the body together.

To prevent the accidental disengagement of link 7 from hook 4, I provide a tongue 8 of resilient material, and preferably secure it to the body 1 by sweating or soldering, as that insures a smooth joint and surface. The said tongue has its free end overlapping the hook 4 and is there recurved as at 9, so 95 that when the two side members of body 1 are pressed together as indicated in Figure 3, the link 7 will not become disengaged from the hook 4, but will be directed away from the end of the hook by the said recurved end, as also indicated in Figure 3, and will snap back into the hook when released. In order to disengage the link 7 from hook 4 to open the lock, the body must be compressed as shown in Figure 3, and the 105 110

- operator must then with his other hand, push the link back and over the beveled edge 5, thereby releasing the jaws from engagement with each other.
- 5 The tongue 8 normally bears and rests upon the sharp chamfered edge 5 of the hook 4, and is only displaced therefrom by the link, but the link cannot pass this edge because of the recurved end 9 of the tongue.
- 10 Thus the fastener can only be opened by the positive action of the operator.

10 represents a guard and is preferably a continuation of the material of the tongue 8, bent back upon itself as at 11, and continued to within close proximity of the hook 4, allowing sufficient space therefrom for the link 7 to pass between. This terminus of the guard has depending flanges 12 secured to a side of the body 1, and is spaced therefrom a sufficient depth to house and allow the tongue 8 to normally contact the edge 5. This construction protects the tongue under all conditions of the washing process with its irregular tumbling and contacting of bags, and insures the free movement of the tongue only when its movement is desired.

Near the recurved union of the tongue and guard, a lip 13 is struck up from the guard and pointed inwardly and upwardly as at 14, for the purpose previously described.

I preferably make the body member of my fastener carrying the link, a little shorter in length than the other member, so that the axis of the eye of the former member shall be positioned inward a little to that of the axis of the inturned hook, for a further precautionary measure, so that the link will normally move away from the end of the hook, as shown in Figure 3, when the body is compressed.

In use, the mouth of the bag is compactly folded and the fastener with lip 13 positioned up is slipped around its folded neck, and link 7 seated and snapped to position within the hook 4, thus closing and locking the bag. Any slippage or opposed movement between the fastener and bag will be immediately checked by the engagement of the lip piercing the mesh of the bag.

I claim:

1. A bag fastener, comprising two body members adapted to approach and recede from each other, one of said members having an inturned end and an inturned hook at the extremity of said end, a tongue adapted to contact the said hook, and a guard housing the said tongue, and the other of said body members having a link hinged thereto at its extremity and adapted to engage the said hook, the said guard prevent-

ing the disengagement of said link when the fastener is closed.

2. A bag fastener, comprising two body members adapted to approach and recede from each other, one of said members having an inturned end and an inturned hook at the extremity of said end, a tongue having a recurved end, adapted to contact said hook, and a guard for said tongue formed by the continuation thereof, the hook having a chamfered edge where it contacts the said tongue, and the other body member having a link hinged thereto, adapted to engage the said hook and said recurved end of said tongue, and the said guard provided with an inwardly-projecting lip to prevent slippage of said fastener when in service.

3. A bag fastener comprising two body members adapted to approach and recede from each other, one of said members having an inturned end and an inturned hook at the extremity of said end, a tongue adapted to contact said hook, and a guard housing the said tongue, and the other body member having an outward-turned end forming an eye thereon, and a link hinged in said eye, the said link adapted to engage the said hook on said first named member, the said guard preventing the disengagement of said link when the fastener is closed.

4. A bag fastener, comprising a resilient metallic strip bent back toward itself forming jaws thereby, a tongue secured to one jaw and bent back upon itself and secured to said jaw forming a guard thereby, and a link secured to the other jaw; the said jaws formed with flat curvatures and with their crowns extending outwardly, one of said jaws provided with an inturned hooked extremity engaging the said tongue and adapted to be engaged by the link on the other jaw, the tongue preventing the link from accidental disengagement in conjunction with said guard when the fastener is in service.

5. A bag fastener, comprising two body members adapted to approach and recede from each other, one of said members having an inturned end and an inturned hook at the extremity of said end, and the other body member having a link hinged thereto and adapted to engage the said hook, the latter body member being shorter in length than the former body member, for directing the link away from the end of said hook when engaged therewith and when the said body members are compressed, and one of said body members provided with an inwardly-projecting lip to prevent slippage when in service.

In testimony whereof I affix my signature,
BERT L. HERRICK,
